UNITED STATES PATENT OFFICE.

COLUMBUS K. ROGERS, OF SALEM, MASSACHUSETTS.

AUTOMATIC ELEVATOR-BRAKE.

SPECIFICATION forming part of Letters Patent No. 313,451, dated March 3, 1885.

Application filed November 12, 1884. (No model.)

To all whom it may concern:

Be it known that I, COLUMBUS K. ROGERS, of Salem, in the county of Essex, in the State of Massachusetts, a citizen of the United States, have invented a new and useful Improvement in Automatic Elevator-Brakes, of which the following is a full, clear, and exact description, reference being had to the accompanying drawings, forming a part of this specification, in explaining its nature.

This invention relates to means for stopping the descent of an elevator in case the hoisting-rope should part. Its details will readily be understood from the following description.

In the drawings, Figure 1 is an elevation. Fig. 2 is a transverse section on the line Q. Fig. 3 is a transverse section on the line P. Fig. 4 is an enlarged view of the braking apparatus, wedge, and shoe. Fig. 5 is a transverse section of the wedge F at line X X.

A is the floor of the elevator.

J J indicate the floors of the building which it serves.

L is the hoisting-beam, which carries the hoisting pulley or drum O.

T is a sill at the bottom of the elevator-shaft. It serves as the anchorage of brake-rods D, and any proper anchorage is its equivalent.

B is the head of the elevator, which is a frame for containing the elevator part of the braking apparatus.

11 are the uprights of the elevator-shaft, and R R are the fixed guides on which or in which counterpart guides in the elevator-car fit.

C are the uprights of the elevator-car, which connect the head B and bottom A of the car. Just inside these uprights, from top to bottom 40 of the elevator-shaft, are stretched the brake-rods D, represented in the drawings as wire ropes. They are represented as passing through beam L and through cup-washers above it, and as spread and wedged in these 45 washers; but any other suitable way of making the upper ends of these rods fast to the beam L may be adopted. These rods D are anchored at M at the bottom of the elevator-shaft. A box, E, is formed at each end of the 50 head-beam B, the outer end of which is just clear of brake-rod D. The hoisting-rope N

passes through an eyebolt, which lays hold of head-beam B through the spring H.

In the head-beam B are a pair of levers, G, hitched to the eyebolt, the outer ends of which engage with wedges F. It will be seen that by this arrangement the weight of the car will compress the spring H, lift the inner ends of levers G, and lower the outer ends so long as hoisting-rope N sustains the car, while if the rope N be parted the extension of spring H will lift the outer ends of levers G and raise the wedges F. These wedges F have a tongue, F', formed on them, which tongue F' bears against the brake-rod D in a recess of the box E. (Shown particularly in Fig. 3.) Each wedge F has on its inner side two inclined planes terminated by hooks at their upper ends, and the thin ends of the wedges are up. Two transverse bolts, S, are under the hooks 70 of the wedges, and the wedges normally rest on these bolts. Bolts S extend across box E in the end of head-beam B. When the levers G are moved by the spring H to raise the wedges F, the inclined planes on the back of the wedges run up against the bolts S, and the tongue F' nips the brake-rod D between it and the end of box E, and the descent of the car is checked.

In former use of wedges to check the descent of an elevator-car when the rope breaks, the wedges have been made to bite on the cheeks of the vertical guides in the elevator-shaft. In this, special suspension-rods (called above "brake-rods") are provided, and no reliance is placed on the guides or ways. It is comparatively easy to make the box E in the head-beam B strong enough not to be sprung by the wedges; but when the braking-wedges are brought to bear against the ways they must be 90 braced from outside not to spring.

It is obvious that the brake-rods might be made stout enough to act as vertical ways; but in this case they would be brake-rods as well as ways.

Having thus fully described my invention, I claim and desire to secure by Letters Patent of the United States—

1. The combination, with the car of an elevator and its hoisting-rope, of the spring H, 100 adapted to be compressed by the weight of the car when suspended by the hoisting-rope and

to extend when the hoisting-rope gives way, in combination with levers G, wedges F, and pins S, arranged in the box E at either end of the head-beam, and in further combination 5 with brake-rods D, extended from one end to the other of the elevator-shaft, whereby on the parting of the hoisting-rope the brake-rods D are seized by the brake F and box E, substantially as described.

2. In combination with the box E at the 10 end of the head-beam of an elevator-car, the transverse pins S and wedge F, adapted in its vertical motion to be driven toward the end of the box E, substantially as described.

COLUMBUS K. ROGERS.
